BUFFING COOLING MECHANISM

John C. Wisnieski, Detroit, and Wayne A. Martin, Berkley, Mich., assignors to Lyon Incorporated, Detroit, Mich., a corporation of Delaware

Application April 10, 1957, Serial No. 652,013

7 Claims. (Cl. 51—266)

This invention relates generally to a new and improved air cooled buffing machine construction.

More particularly, this invention relates to a new, improved and highly simplified buffing machine construction which machine is especially adapted to maintain the buffs during buffing in a cooled state so as to lengthen the life span of the buffs.

Still another object of this invention is to provide new and improved means for controlling the movement of air through the buffing machine including passages for generally radially moving air into passages in the drive shaft and then moving the air radially outwardly through the drive shaft into the buff to cool the same.

A further object of this invention is to provide a new and improved air cooling system for a buffing machine for cooling the buffs during a buffing operation which system constitutes an economical installation and is highly efficient in cooling the buffs.

According to the general features of this invention there is provided in an air cooled buffing machine, a housing having an internal bore, a drive shaft rotatably mounted in the bore having an axially extending air passage intermediate opposite ends of the drive shaft, a buffing wheel structure carried on the shaft in overlying relation to the generally axial air passage, a plurality of generally radial air passages between the axial air passage and the buff structure for cooling same, axially spaced shaft seal assemblies between the drive shaft and the housing, a compressed air chamber disposed generally axially between the shaft seal assemblies and generally radially between the drive shaft and the housing with the chamber having a compressed air inlet, at least one generally radial passageway between the axial shaft air passage and the compressed air chamber with air moving from the compressed air inlet through the chamber into the passage in the shaft and then along the passage and out through the radial air passages for cooling the buffing wheel structure, the shaft having a spiral groove therein linking the plurality of radial air passages to aid in the uniform direction of air through the buffing wheel structure.

Other objects and features of the present invention will more fully become apparent in view of the following detailed description taken in conjunction with the accompanying sheets of drawings illustrating therein a single embodiment, and in which:

Figure 1 is a radial cross-sectional view of the buffing machine of this invention with parts broken away in full lines highlighting certain features;

Figure 2 is an enlarged fragmentary side elevation of a buffing wheel; and

Figure 3 is an enlarged fragmentary cross-sectional view taken on the line III—III of Figure 2 looking in the direction indicated by the arrows.

As shown on the drawings:

The reference numeral 10 indicates generally our buffing machine. The buffing machine includes a tubular housing 11 carried by a conventional ball bearing assem-

bly 12 upon a drive shaft 13 which may be driven in any suitable manner.

The drive shaft 13 may be formed from any suitable material and has a series of shaft sections of varying diameters including shaft sections 13a, 13b, 13c, 13d, 13e, 13f and 13g. Extending through the axially outer end of the shaft section 13g is a continuous longitudinal passageway 14 extending axially to shaft section 13c which is of a reduced diameter as compared to the shaft section 13b and 13d. To seal off the axially outer end of the shaft section 13g, a plug 15 is fitted into sealed engagement in an end portion of the longitudinal passageway 14.

To further support the shaft 13 and to provide a sealed compressed air chamber 16, shaft seal assemblies 17 and 18 are carried by the shaft sections 13b and 13d respectively. The shaft assemblies are constructed in such a manner that the compressed air chamber 16 is generally defined at its outer periphery by the seal assemblies 17 and 18. In communication with the compressed air chamber 16 is a compressed air conduit 19 having an inlet 20 into the chamber 16. To connect the longitudinal shaft passageway 14 with the chamber 16, a radial passageway is provided in the reduced shaft section 13c so that air may move through the conduit 19, through the inlet 20 and into the chamber 16 whereupon the air may then flow into the longitudinal extending shaft passageway 14.

According to certain features of the present invention the shaft section 13g is provided with a continuous rather sharply pitched spiral groove 22 suitably formed in the shaft by machine operations and the like. At suitable intervals the groove 22 is drilled to provide a plurality of radially extending channels or passageways 23 connecting the groove with the longitudinally extending shaft passageway 14. Mounted on the reduced shaft section 13g is a buff or buffing wheel 24 comprised of a plurality of annular buff sections 25. Cool air is discharged from the ports of the passageways 23 into the inner confines of the annular buff structure to cool the same.

The housing 11 has a tubular housing wall 24 which is internally formed so as to provide wall sections 24a and 24b of varying internal diameters with an annular axially outwardly facing shoulder 25 between the sections 24a and 24b. The shaft assembly 17 is in abutting engagement against the annular shoulder 25.

Since the construction of the shaft assemblies 17 and 18 are substantially identical, primed reference numerals have been utilized to identify identical elements in the shaft assembly 18.

The shaft seal assemblies each have a pair of annular blocks 26, 26' and 27 and 27' with the blocks 26, 26' each being generally L-shaped in cross section.

Disposed between each of the pairs of blocks previously described is an annular ring 28, 28' having a ring mounting 29 and 29' lodged or seated within an internal pocket in the ring 28, 28' and supporting the assembly upon the shaft. The ring mountings may be made from any suitable material such as neoprene and are adapted to be carried upon the drive shaft sections 13b and 13d as the case may be. To seal the junction between the blocks 26, 26' and 27, 27' with the drive shaft, O-ring seals 30, 30' are disposed at the junction of the aforementioned blocks with the inner casing wall. These rings serve to preclude air and oil from moving axially along the shaft and escaping.

To maintain the blocks 28, 28' in position, the blocks 26, 26' are provided with radially inwardly extending extensions 31, 31' which extensions cooperate with the generally L-shaped blocks 26, 26' to define pockets. Disposed in the pockets and between the shaft and the blocks 26, 26' are lodged retainer ring members 32, 32'. Bearing against the retainer members 32 are

springs 33, 33'. The springs on each assembly bear at one of the axial ends against one of several pairs of carbon blocks 34, 34' with carbon blocks on axially opposite ends of the annular seat members in abutting engagement therewith.

On the other side of the seat member 28 is disposed an annular plate 35, 35'. Each of the plates 35, 35' is in interlocked assembly with one of the block members 27, 27'.

Disposed between the plate member 35, 35' and the block member 28, 28' is the retainer ring 36, 36', the springs 33, 33' and the carbon block 34, 34', which carbon blocks bear against the member 28, 28'. Due to the spring forces exerted against the carbon blocks the carbon blocks are maintained in abutting engagement against the ring member 28, 28'. Because of the close fit between the carbon blocks 34 with respect to the rotating ring member 28 an oil tight seal is created.

Positioned above the member 28, 28' is an oil receptacle 35, 35' which is adapted to permit oil to be metered into a chamber above the member 28, 28' and between the block members 26, 26' and 27, 27' to lubricate the end faces of the carbon blocks with respect to the rotary ring member 28, 28'. Hence, at all times, the carbon block due to the spring force are maintained in snug engagement against the rotary ring member 28, 28'.

In abutting engagement against the seal assembly 18 is the ball bearing assembly 12 which assembly 12 is carried on the reduced shaft section 13e.

To maintain the ball bearing assembly in snug engagement against annular shoulder 36a between the sections 13d and 13e, shaft section 13f is threaded at 37. Pressed against the ball bearing assembly is a washer 38 and a nut 39 is threaded upon the threads 37 to snugly urge the roller bearing assembly 12 against the shoulder 36a. To lock the nut in position, the washer portion 38 is turned into a notch in the nut 39 to maintain the nut in firm assembly with the rotary portion of the roller bearing assembly 12.

Disposed over the end of the housing 11 is a closure cap 40 which is bolted to the casing wall by means of screws 41.

The buffering wheel 24 is of the general order of the buffering wheel disclosed in the John C. Wisnieski application for patent entitled "Buffing Wheel Structure," Serial No. 401,560, filed December 31, 1953.

Each annular section 24 is comprised of a plurality of layers of buffering material which may be sisal type fibers or cloth or other suitable materials. The plies of each buffering section 24 are held together and carried in assembly by annular rings 42 and 43. Each of the rings 42 has an annular flange 44 for engaging against the outer surface of the shaft section 13g. Upwardly from the flange 44, the ring 42 has a spacer flange 45 which has a series of circumferentially spaced ports or openings 46 for facilitating movement of air axially through the buffering wheel. Upwardly from the annular spacer flange 45 the ring 42 is of a stepped construction including annular flanges 47 and 48 with annular flange 47 being concentric with annular flange 44 and annular flange 48 being concentric with annular flange 45. It will be noted in Figure 2 that the flange 48 is corrugated or undulated to provide a series of radially extending channels or air passageways 49 when ring 43 is in assembly therewith.

In more detail, the ring 43 is generally C-shaped in cross section including a series of circumferentially spaced inner generally axially extending flange portions or prongs 50, a generally radially outwardly extending annular end flange portion 51, and a series of circumferentially spaced generally axially extending flange portions or prongs 52.

Where the prongs 50 and 52 are stationed there is positioned radially therebetween an axially offset rib 53 which extends in a generally radially outwardly direction

and defines with the inner ring 42, and more particularly with the annular flange portion 48, enlarged passages or air channels 54 (Figure 3).

Assembly of the buffering sections upon the drive shaft 13 may be brought about by initially slipping a ring member 55 onto the shaft 13 and moving the ring member axially against the shoulder 56 at the junction of the shaft section 13f and 13g. Thereafter each of the individual annular buffering sections 24 may be aligned with the shaft and moved thereover against the ring member 55. At this point a second ring member 57 is centered with respect to the shaft 13 and engaged therewith while being moved against the axially outermost buffering section 25. A nut 58 is then threaded onto the threaded end 15 of the shaft section 13g to clamp the buffering sections 25 together to form a buffering wheel 24.

It will be appreciated that as the air is discharged radially through the ports 23 the air is free to further move radially or axially in the buffering wheel. The air may move axially between the various buffering sections through the helical groove 22 and also through the openings 46. The air is free to move radially in the buffering wheel by virtue of the channels or passages 49 and 54 in the ring members 42 and 43 which ring members also serve to secure the plies of each of the buffering sections in assembly with one another.

The plies may be secured with the ring members 42 and 43 of each buffering section 25 by initially moving the plies against the angular annular shoulder defined by angled flanges 47 and 48. The C-shaped ring 43 is then moved axially with respect to ring 42 with prongs 50 overlapping ring flange 47 of ring 42 and with prongs 52 overlapping the radially outermost tip of flange 48 of ring 42 and being embedded in the plies of buffering material. The plies of the buffering may be glued or sewn together if desired.

It will be understood that modifications and variations may be effected without departing from the scope of the novel concepts of the present invention.

We claim as our invention:

1. In an air cooled buffering machine, a housing having an internal bore, a drive shaft rotatably mounted in said bore having an axially extending air passage intermediate opposite ends of said drive shaft, a buffering wheel structure carried on said shaft in overlying relation to said generally axial air passage, a plurality of generally radial air passages between said axial air passage and said buffering structure for cooling same, axially spaced shaft seal assemblies between said drive shaft and said housing, a compressed air chamber disposed generally axially between said shaft seal assemblies and generally radially between said drive shaft and said housing with said chamber having a compressed air inlet, at least one generally radial passageway between said axial shaft air passage and said compressed air chamber with air moving from said compressed air inlet through the chamber into the passage in the shaft and then along the passage and out through the radial air passages for cooling the buffering wheel structure.

2. In an air cooled buffering machine, a housing having an internal bore, a drive shaft rotatably mounted in said bore having an axially extending air passage intermediate opposite ends of said drive shaft, a buffering wheel structure carried on said shaft in overlying relation to said generally axial air passage, a plurality of generally radial air passages between said axial air passage and said buffering structure for cooling same, axially spaced shaft seal assemblies between said drive shaft and said housing, a compressed air chamber disposed generally axially between said shaft seal assemblies and generally radially between said drive shaft and said housing with said chamber having a compressed air inlet, at least one generally radial passageway between said axial shaft air passage and said compressed air chamber with air moving from said compressed air inlet through the chamber into

the passage in the shaft and then along the passage and out through the radial air passages for cooling the buffing wheel structure, said shaft having a spiral groove therein linking the plurality of radial air passages to aid in the uniform direction of air through the buffing wheel structure.

3. In an air cooled buffing machine, a housing having an internal bore, a drive shaft including main and end shaft portions rotatably mounted in said bore with the end shaft portion having a reduced diameter as compared with the main shaft portion and with a shoulder at the junction of the shaft portions, said shaft having an axially extending air passage extending axially outwardly from the housing into the end shaft portion, a buffing wheel structure comprised of a multiplicity of annular buff sections in abutting relation to one another with the buff section in closest proximity to said shoulder abutting thereagainst and with said sections positioned in overlying relation to the generally axial air passage in said end shaft portion, a plurality of generally radial air passages between said axial air passage and said buff structure for cooling the same, axially spaced shaft seal assemblies between said drive shaft and said housing, a compressed air chamber disposed generally axially between said shaft seal assemblies and generally radially between said drive shaft and said housing with said chamber having a compressed air inlet, at least one generally radial passageway between said axial shaft air passage and said compressed air chamber with air moving from said compressed air inlet through the chamber into the axially extending air passage in the shaft and then along the shaft and out through the radial air passage for cooling the buffing wheel structure, and clamp means on said end shaft portion urging said buff sections into snug engagement with one another and against said shoulder.

4. In an air cooled buffing machine, a drive shaft having an axially extending air passage intermediate opposite ends of said drive shaft, a buffing wheel structure carried on said shaft in overlying relation to said generally axial air passage, said buffing wheel structure including a plurality of annular buff sections, each of said buff sections including a mounting ring and a ring of buffing material mounted in assembly therewith, said rings having axially offset portions defining radially outwardly opening passages between the buff sections to permit air to pass between the buff sections, a plurality of generally radial air passages between said axial air passage and said passages in said buff structure for cooling the buff, and a spiral groove in said shaft underlying said buffing wheel structure with said groove having said radial air passages therein to aid in the distribution of air radially outwardly through the buffing structure.

5. In an air cooled buffing machine, a drive shaft having an axially extending air passage extending along the

length of said drive shaft, a buffing wheel structure carried on said shaft in overlying relation to said generally axial air passage, said buffing wheel structure including a plurality of annular buff sections, each of said buff sections including a mounting ring and a ring of buffing material mounted in assembly therewith, said rings having axially offset portions defining radially outwardly opening

10 passages between the buff sections to permit air to pass between the buff sections, a plurality of generally radial air passages between said axial air passage and said passages in said buff structure for cooling the buff, and a spiral groove in said shaft underlying said buffing wheel structure with said groove having said radial air passages therein to aid in the distribution of air radially outwardly through the buffing structure.

15 6. In an air cooled buffing machine, a centrally bored drive shaft which bore defines an axially extending air passage extending along the length of said drive shaft, a buffing wheel structure carried on said shaft in overlying relation to said generally axial air passage, said buffing wheel including an annular fiber buff structure and mounting ring structure supporting the fiber buff structure upon the drive shaft, said buffing wheel also including a plurality of circumferentially disposed radially extending air 20 passages for cooling the buff, said shaft being peripherally grooved with the radially extending air passages in communication therewith, and with the drive shaft including the peripheral groove having radial air passageways communicating the peripheral groove with the axially extending air 25 passages, said radially extending air passageways being cooperable with the peripheral groove and the radial passages to aid in the distribution of air from the axially extending air passage radially outwardly through the buffing structure, and retaining structure for fastening 30 the buffing wheel structure to the drive shaft.

35 7. In an air cooled buffing machine, a housing having an internal bore, a drive shaft rotatably mounted in said bore having an axially extending air passage intermediate opposite ends of said drive shaft, a buffing wheel structure 40 carried on said shaft in overlying relation to said generally axial air passage, at least one air outlet passage between the axial air passage and the buff structure for cooling same, axially spaced air seals between the drive shaft and the housing, a compressed air chamber disposed generally radially of the drive shaft, with the chamber having a compressed air inlet, at least one generally radial air inlet passageway between the axial shaft air passage and said compressed air chamber with air moving from said compressed air inlet through the chamber into the air inlet passage in the shaft, and then along the axially extending air passage and out through at least one air outlet passage for cooling the buffing wheel structure.
